UNITED STATES PATENT OFFICE.

INGEBOEG MARIE JENSEN, OF CHICAGO, ILLINOIS.

CROCHET-NEEDLE AND HOLDER.

1,289,470.

Specification of Letters Patent.

Patented Dec. 31, 1913.

Application filed February 10, 1917. Serial No. 147,825.

To all whom it may concern:

Be it known that I, INGEBOEG MARIE JENSEN, a citizen of the United States, and a resident of Chicago, in the county of Cook and State of Illinois, have invented certain new and useful Improvements in Crochet-Needles and Holders, of which the following is a full, clear, and exact specification.

My invention is concerned with improvements in crochet needles, and is designed to produce a crochet needle that can be used to accumulate a very considerable number of stitches on the needle before they are disengaged therefrom, and also to produce a needle that is adjustable in its holder to vary the amount of the needle that is exposed from the holder so that it can be used most effectively to accumulate any desired number of stitches on the needle.

26 It is further designed to produce a crochet needle that can be adjusted as desired in a flattened holder so that it cannot possibly turn therein and get the hook standing at the wrong angle in relation to the hand.

25 It is further designed to produce a holder for a crochet needle that may have the function of embracing some of the work already crocheted to protect it from being soiled as additional stitches are added.

30 To illustrate my invention, I annex hereto a sheet of drawings, in which the same reference characters are used to designate identical parts in all the figures, of which.—

Figure 1 is a perspective view showing how my needle and holder are used;

Fig. 2 is a view of the needle in the holder; and

Fig. 3 is a cross section on the line 3—3 of Fig. 2, but on a much enlarged scale.

40 In carrying out my invention in its preferred form, I employ a needle preferably constructed of a single piece of metal, and having the central body portion 10 of uniform cross section throughout said body portion, said cross section preferably taking the form of a rectangle with rounded corners so as to present one or more flattened sides to prevent its turning in the holder. In connection with the body portion 10, I of course employ one or two hooks 11, which are connected with the body portion 10 by a tapered portion 12 in the customary manner.

In its preferred form, I make the holder 13 of a sheet of celluloid, which is of a generally oblong shape and is folded along its

longitudinal center, preferably with the portion near its outer edges projecting so that when the needle is not in place the portions near the edges contact, as indicated in dotted lines in Fig. 3. The design is such that when the needle is shoved in place, its flattened sides spread the sides of the holder, and the outer edges are preferably curved out slightly, as seen at 14, so that in use the open edge of the holder can be slipped over the work 15, as seen in Fig. 1, to protect it. The elasticity of the holder is sufficient to secure the needle in any desired position of longitudinal adjustment therein, and it will be perfectly obvious that as much of the body portion of either end can be made to extend from the holder as may be advisable in taking any desired number of the stitches on the needle at a single time.

What I claim as new, and desire to secure by Letters Patent of the United States, is:

1. A crochet needle having its body portion flattened on one or more sides for the purpose described, a hook, and a tapering portion connecting the hook and the body portion, in combination with a holder in which the needle may be adjusted longitudinally, said holder having a flattened exterior portion, and a flattened interior portion co-operating with the flattened side of the body portion of the needle to secure the hook at the proper angle to the flattened exterior of the holder, said holder having one side thereof open so that it may embrace and protect a portion of the work.

2. A detachable holder for a crochet needle consisting of a generally oblong sheet of rigid elastic material, said sheet being folded along the center to give it the shape of an elongated U in cross section when the needle is inserted.

3. A detachable holder for a crochet needle consisting of a generally oblong sheet of rigid elastic material, said sheet being folded along the center to give it the shape of an elongated U in cross section when the needle is inserted, and having its longer side edges curved away from each other.

In witness whereof, I have hereunto set my hand and affixed my seal this eighth day of February, A. D. 1917.

INGEBOEG MARIE JENSEN. [p. sq]

Witness:

JOHN HOWARD McELROY.
